UNITED STATES PATENT OFFICE.

CURTIS T. CLIFFORD, OF SAN FRANCISCO, CALIFORNIA.

DRY PIPE MECHANISM FOR AUTOMATIC SPRINKLER SYSTEMS.

Application filed March 31, 1919. Serial No. 283,561.

To all whom it may concern:

Be it known that I, CURTIS T. CLIFFORD, a citizen of the United States, and a resident of the city and county of San Francisco, State of California, have made a new and useful invention—to wit, an Improvement in Dry Pipe Mechanism for Automatic Sprinkler Systems; and I hereby declare the following to be a written description of the same in such full, clear, concise, and exact terms as to enable any person skilled in the art to which it appertains or to which it is most nearly connected to make, construct, and use the same.

15 The principal object of my device is to so arrange the structure as to allow the instant action at a predetermined degree of pressure of the same, as soon as the air pressure is reduced by the melting of a sprinkler head at

20 some point in the system.

Another object is to provide a device which is simple in operation and easily accessible for the purposes of repair or adjustment.

25 Referring to the drawings:

Figure 1 is a cross section of the valve structure as a whole showing the valves in their normal positions in full lines, and in operating position in dotted lines.

30 Fig. 2 is a cross section of Fig. 1 taken on the line X—X.

Fig. 3 is a detail enlarged view of the tumbler mechanism and its associated parts about the valve 13 of Fig. 1 with some of the otherwise obscuring parts shown dotted.

35 Referring more in detail to the drawings, the same numerals refer to corresponding parts in the several views. The numeral 5 designates the main casting of the entire structure and the numeral 6 the auxiliary casting which houses the valve connecting mechanism.

40 The numeral 7 refers to a flanged water supply inlet and 8 to a flanged outlet to the sprinkler system.

45 Substantially midway of the casting I provide a horizontal partition 9 having an opening therein. Threaded into said opening is a valve seat 10 and upon this valve seat rests the valve 11, which is hinged to the casting 5 by means of a pintle 12.

50 Above said inlet 7 I place a valve 13 which is normally held upon its seat 14 by a system of levers which will be hereinafter described in detail.

55 In an offset portion 15 of the casting 5, I

provide an opening 16 and a valve seat 17 secured within said opening. Seated upon said valve seat is a pilot valve 18 hinged at 19 to the casting 5. Above this valve 18 I 60 provide a hand hole and suitable cover 21 held in place by bolts 22. Upon the cover 21 and casting 5 I place lead buttons or abutments 23 against which the valves 11, 13 and 18 will strike upon opening.

65 Below the valve 18 and carried by a pin 24, I mount a trigger or latch 25, said pin being carried by the valve seat ring 17 and passing through a slotted opening 26 in said trigger.

70 Within said auxiliary casting 6 and below the trigger 25, I mount upon a pin 48 a rotatable irregular shaped weight 27 having a nose 28 adapted to engage the lower end of the trigger 25, and below said weight I place 75 a rotatable cam shaped lever, the upper horn or second latch 29 of which is adapted to rest against the weight 27 at the point 30.

75 The lower horn of the lever forms a hook for engagement with a supporting or adjusting screw 31, which is capable of adjustment through the nut and lock nut 32 and 33. The movement of this adjusting screw is controlled by pins 44 moving in grooves upon the sides of the auxiliary casting 6. The 80 lower end of this screw is pivotally connected at 34 to a link or lever of the first order 35 having a valve disc or diaphragm 36 for closing the opening from chamber B when pressure is admitted thereto from C, and this 85 is accomplished by the said disc seating at 37 in the casting 5 and as shown in dotted lines in Fig. 1. The other end of the lever 35 is pivoted at 59 to the link 45 which is 90 adapted to swing about the pivot 57.

95 At 39 is a horn or tit on said lever 35, which engages the tumbler 38 when the parts are in the full line position of Figs. 1 and 3, and holds said tumbler in locked engagement with the member 40 with which is associated the valve disc 13 and which is kept tightly depressed on its seat 14 by the sloping face 53 of said tumbler. The tumbler 38 is pivoted at 55 to the member 56 loosely mounted on the pivot 57 so that the several 100 parts as follows may be freely forced to the right by the pressure on 13 and 40. Thus when the tit 39 is released the lever 56, link 45, tumbler 38 will be forced violently to the right, see also Fig. 1.

105 Drains are provided at 42 and 43 for the chambers 6 and A respectively. The weight

27 is limited in its movement by a projection 46 and lead button 47.

It will be seen that when the link mechanism 31 is permitted to fall through the 5 opening of valve 18 and the tripping of the several connections therebetween, the first action will be a swinging of the lever 35 about the pivot 59 at which time the tit 39 will move upward into the dotted position 60. This will free the pressure contact heretofore existing between the tit 39 and tumbler 38 whereby the member 40 has been held down compressing the valve 13 upon its seat 14, and the entire strain of this 15 holding pressure has been supported by the link 45 and pins 59 and 57, the link having been under heavy tension due to the link mechanism 31 having been held in its up position.

20 When the tumbler 38 has been freed as above described, as shown more clearly in Fig. 3, it will rotate about the pin 55 to the dotted position 58, thus releasing the member 40 and valve 13 which may now swing 25 freely upward about the pivot 41 clearing the passage for high pressure water. In order to facilitate the clearing of the lever 35 link 45 the bell shape valve 36 receives some of the pressure water which is first allowed to leak into the chamber B when the tit 39 is first moved into the dotted position 60 and this pressure water before the valve has opened any considerable amount will force against the valve 36, causing its closure on the seat 37 and thus cause the movement toward the right of the lever 35 and its link 45. It is to be understood that the tumbler 38 may swing freely at all times about the pivot 55 which I have shown supported by the connecting link 56 from the main supporting shaft or pin 57, except such times as it is employed as an intermediate compression member between 40 and the tit 39.

I claim:

1. In a main valve for supplying a sprinkler system, a compartment normally containing compressed air and a compartment open to the atmosphere and a connection for high pressure water supply thereto; a main valve member closing said water connection from said atmospheric chamber; a one-way valve between said atmospheric chamber and said compressed air chamber normally held on its seat by said compressed air; a pilot valve within said compressed air chamber normally held upon its seat by compressed air and mechanism including a trigger, a pivoted weight, a latch, a link including means constructed and adapted to vary its length, a lever carrying a valve, a tumbler engaged by the lever, said tumbler engaging the main valve member to retain it in normal closed position; said mechanism co-operating with said pilot valve, so that upon the release of the compressed air from the compressed air compartment the pilot valve opens releasing the mechanism which in turn releases the main valve member.

2. In a main valve for supplying a sprinkler system as set forth in claim 1, and a member carrying said tumbler at one end and loosely pivoted on the other whereby the tumbler is allowed a freedom of movement on the release of the mechanism by the pilot valve.

3. A main valve for supplying a sprinkler system as set forth in claim 1 wherein said weight is pivotally mounted to swing about an axis without lost motion.

In testimony whereof, I have hereunto set my hand at San Francisco, California, this 19th day of March 1919.

CURTIS T. CLIFFORD.

In presence of—

BRADLEY L. BENSON,
P. S. PIDIVELL.
